DISPENSER CAP FOR A PRESSURIZED CAN

Robert H. Abplanalp, 10 Hewitt Ave., Bronxville, N.Y.

Filed Oct. 29, 1963, Ser. No. 77,191

Term of patent 14 years

(Cl. D58—26)

FIG. 1 is a rear perspective view of a dispenser cap for a pressurized can, showing my new design;

FIG. 2 is a top plan view thereof;

FIG. 3 is a front perspective view thereof;

FIG. 4 is a front elevational view thereof;

FIG. 5 is a side elevational view thereof; and

FIG. 6 is a rear elevational view thereof.

I claim:

The ornamental design for a dispenser cap for a pressurized can, as shown.
